UNITED STATES PATENT OFFICE.

FRANK PARKER BLODGETT, OF CHICAGO, ILLINOIS, ASSIGNOR TO LODOSCA SULLIVAN, OF SAME PLACE.

WATER-HEATER.

SPECIFICATION forming part of Letters Patent No. 425,062, dated April 8, 1890.

Application filed April 19, 1889. Serial No. 307,693. (No model.)

To all whom it may concern:

Be it known that I, FRANK PARKER BLODGETT, a citizen of the United States, residing in Chicago, in the county of Cook and State of Illinois, have invented a new and useful Improvement in Hot-Water Heaters, of which the following is a specification.

My invention relates to hot-water heaters of the type wherein the heater consists of a number of horizontal sections laid one on top of another. In hot-water heaters of this type heretofore in use the water ports or connections between the several sections have usually been in the form of columns placed at the outer side or at the corners of the heaters, forming an open passage from the top to the bottom of the heater. This manner of placing the water-ports as well as the construction and arrangement of the sections with perfectly flat horizontal surfaces is an objectionable arrangement, in that it is impossible to predetermine in what direction the water will flow, it being more liable to run up the columns and cut the sections out than to pass through them, as on account of the level portions of the section, especially in the center, there is nothing to invite a circulation of the water through them, but everything to produce rapid flow of the water up the columns, or if it is circulated through the central portions of the sections the water may flow one way one time and another way the next time, never exactly in the same direction. This intermittent and uncertain flow of the water is very detrimental, in that it destroys to a large degree the effectiveness of the apparatus. This tendency of the water to pass out on the outside of the heater, where the ports between the sections are arranged in vertical lines or columns, one above another, leaves the center of the heater, where the largest portion of the heat is passing, with very little of the work to do, and the heater so constructed is consequently wasteful of the fuel, as the heat passes away through the flues. In this old type of heaters, also, the flues or passages through the sections for the products of combustion have been in the form of round, oval, or narrow openings, passing vertically through the sections, usually in staggered positions, in all arrangements of which the distance through which the products of combustion pass from the fire-box to the

smoke-pipe is so short that a very large per cent. of the heat is wasted by passing to the chimney instead of being absorbed by the water, as it would be if the smoke-passages or flues were longer. In the heaters heretofore in use, also, the manner of placing the water-ports produces a large number of water-joints to be made tight, some of the heaters now in use having as many as thirty-two joints, all of which is objectionable on account of the labor required to make them tight and the increased liability of leaks. In many heaters heretofore in use, also, the lowest water-section into which the water is delivered by the return-pipes is directly in contact with the fire, which on the one hand tends to chill and check the fire, while the intense heat of the fire-pot on the other hand tends to a greater or less extent to drive the water back into the return-pipes and thus to interfere with the circulation of the water through the system.

It is the object of my invention to overcome these difficulties or objections and to produce a hot-water heater of a simple, efficient, and durable construction, and which will produce, first, a positive circulation of the water at all times in a definite and continuous direction; and, second, a maximum absorption of the units of heat from the products of combustion while passing through the heater by the water, and which will have, third, a minimum number of water-joints, all of which I consider to be requisites of a perfect heater.

In my invention the heater is made of a square or rectangular form, so that the water may be made to circulate back and forth across the heater from side to side, and thus prevent the tendency of the water to pass spirally around the outer wall of the heater, as it would tend to do to a greater or less extent if the heater were of a cylindrical form; and I combine with this square or rectangular heater a round fire-pot, so that there may be no waste of fuel by the fire dying out at the corners, as would be the case to a greater or less extent if the fire-pot were square like the heater.

My invention also consists in a hot-water heater having a continuous water space or passage extending in a series of folds or convolutions, one above the other, across the heater from side to side, and a continuous

smoke passage or flue extending in a similar continuous series of folds or convolutions across the heater at right angles to the former, so that the currents of water and the 5 currents of smoke or products of combustion will pass across each other at right angles as they pass through the heater in their respective passages or flues.

It further consists in, in connection with 10 such continuous water and smoke passages, making the water passages or convolutions in a series of inclined planes, one above another, so that the hot water may follow its natural tendency to rise as it passes through 15 the heater, and thus naturally flow across the heater and through the central portion thereof.

It further consists in, in connection with such arrangement of continuous water and smoke passages, making the walls of such 20 water-ways and smoke flues or passages with corrugated surfaces to increase the heating-surface in a small space.

By thus arranging the water ways or passages through the heater in the form of a series of continuous folds or convolutions extending across the heater from side to side, I 25 am enabled to reduce by about one-half the number of water-joints in the heater.

In my heater, as in some old heaters, the 30 lowermost water-section, commonly called the "fire-pot section," and into which the water is delivered by the return-pipes, is provided with a fire-brick lining to prevent the checking of the fire by the chilling action of the water and the interference with the water circulation by the heat of the fire-pot driving the water back into the return-pipes.

Another feature of my invention consists in the construction thereof, as hereinafter 40 described, whereby I am enabled to combine a direct-draft passage with the circuitous or heating passage, the direct draft being used when starting the fire.

My invention also consists in the novel devices and novel combination of parts and devices herein shown and described, and more particularly pointed out in the claims.

In the accompanying drawings, which form a part of this specification, and in which similar letters of reference indicate like parts, Figure 1 is a front elevation of a heater embodying my invention. Fig. 2 is a vertical section on line 2 2 of Fig. 1. Fig. 3 is a vertical section on line 3 3 of Fig. 2. Fig. 4 is a detail plan view, on a somewhat smaller scale, of the fire-pot section. Fig. 5 is a section on line 5 5 of Fig. 2, and Fig. 6 is a horizontal section on line 6 6 of Fig. 2.

In the drawings, A represents the base or 60 ash-pit section of the heater, which has no water-space. Next above the ash-pit section is the fire-pot section B, which contains the water-space b between its inner and outer walls b' b''. The fire-pot section B has a lining of fire-brick B' to prevent the heat from the fire-pot driving the water back into the return-pipes P, and also to prevent the water

70 checking the fire by chilling it. The fire-box section B is also furnished with a grate B², which may be of any usual or known construction. Next above the fire-pot section B is the fire-box section C, having its inner wall or surface c next to the fire corrugated, as is clearly shown in Figs. 3 and 5. Next above the fire-box section C is the crown-sheet section 75 D, having its under surface or crown-sheet d corrugated and provided with a passage E at the rear side for the products of combustion to leave the fire-box and pass into the flue F, extending through the sections G 80 above in a continuous series of folds passing back and forth across the heater from one side thereof to the other. At the rear side of the crown-section D is an opening H to be used as a direct draft when kindling a fire, said 85 opening being connected with the smoke-pipe K by the pipe L, as shown. The draft is controlled by dampers l k, located in the pipes L K, preferably about as shown.

The four intermediate sections G above the 90 crown-sheet sections are all similar in construction, each having the under side g corrugated to increase the heating-surfaces, and each having a water-space g' and forming 95 with the sections above and below a continuous water-space extending from side to side across the heater at right angles to the folds of the flue F in a similar series of folds or convolutions. Above the sections G is the top section M, having its under side m corrugated similar to the sections G and D, and having a vertical opening m' through it for the 100 exit of the products of combustion, the same being connected with the smoke-pipe K. The sections G may vary in number, either less or 105 more. It will be observed that the flue F is in the form of a double S and is formed by the space between the several sections D, G, and N. The gases or products of combustion on 110 their way from the fire-box to the smoke-pipe 115 are thus conducted through a long and extended passage continuously in contact with the water-space, so that the water has opportunity to completely absorb the heat from the products of combustion before the same issues 120 from the heater. At the front side of the heater a series of openings N are provided for cleaning-out purposes, these openings being closed by a door or doors N'. The several sections are bound together by means of short bolts S 125 extending through lugs s, placed at the sides of the sections, binding one section to the other. The water-joints are made tight by means of gaskets s', preferably of asbestos, placed between the faces of the joints. The 130 gaskets may be of any material suitable for the purpose.

The return-pipes P, which convey the water back to the heater, enter the lowermost water-section B, the interior of which has the lining B' of fire-brick or other refractory material. P' represents the outlet-pipe, through which the heated water is conveyed from the heater to the radiator. These outlet-pipes enter the

top section M, and preferably vertical to the top plate thereof. The return-pipes P and exit-pipes P' may be of any size and number desired according to the requirements.

- 5 By referring to the drawings, especially to Fig. 3 thereof, it will be seen that there is but one water-port x between each pair of adjoining sections G, D, or M, and that all the water ways or spaces g' are inclined planes, and 10 that the ports x are so placed that the water must pass through the center of the section, that there are no square corners around which the water turns, and that all the surfaces are smooth and all corners round, thereby reducing the friction to a minimum. It 15 will also be observed that the ports x, in connection with the water ways or passages g' of the contiguous sections, produce a continuous water-passage from the bottom to the top 20 of the heater, no part of which is horizontal, and which extends in a series of folds or convolutions back and forth across the heater from one side thereof to the other. It will also be observed from Figs. 4 and 5 that the 25 water-ports x between the contiguous sections are in the form of oblong slots located centrally at one side of the heater, and that the length of these ports extends almost across the whole side of the heater.
- 30 By referring now to Fig. 2, it will be seen that the smoke flue or passage F also extends in a similar series of convolutions or folds back and forth across the heater at right angles to the series of water-ways, so that the 35 smoke-flues and water-ways cross each other at right angles. The heat or products of combustion, therefore, as they pass through the flue F keep continually crossing the currents of water flowing through the ways g' g', so 40 that every particle of water has opportunity to come in contact with the heat as it passes through the smoke-flues F.

The water enters the heater at either side through the openings in the fire-pot B, as 45 shown, passes thence around the fire-pot and also into the fire-box section C and around the fire-box section, and from these two sections into the crown -sheet section D, and across over the fire through this section and 50 into the section G above it, and across through this section and into the one above it, and through that in the same manner, and continuing through the other upper sections G in the same manner until it reaches the outlet-openings in the upper sections M, by which time it has become thoroughly heated and passes off to the heating apparatus. Thus it will be seen that the water always passes over the fire through the central portion of 55 the sections and cannot pass away from the heater without doing so, the water always finding an easy flow up the inclined planes within the sections.

The products of combustion pass from the 60 fire-box through the flue at the rear side of same into the flue F, placed between the sections, as shown, and through said flue from

rear to front and from front to rear (the heat passing at right angles with the water) until it reaches the smoke-exit at the top of the 70 heater. In this way the heat comes in direct contact (by passing across the surface) with both sides of each section before leaving the heater. This cannot be said of any other heater. In my heater the water thus crosses 75 over the fire seven times and the heat over the water eleven times before they leave the heater.

I claim—

1. In a hot-water heater, the combination 80 of a fire-pot and flue F leading therefrom to the smoke-pipe in a series of folds between the water-spaces of the sections for heating the water, said flue extending from side to side across the heater, and a separate direct draft L, leading directly from the fire-space to the smoke-pipe for use in starting the fire, said latter flue not extending through or between the water-spaces of the heater, substantially as specified. 90

2. A hot-water heater composed of a series of sections laid one on top of another, and having one broad shallow continuous water space or passage the full width of the heater, extending in a series of folds or bends, one 95 above another, across the heater from side to side, the water-spaces of the contiguous sections communicating together by long narrow centrally-located ports at the ends of the sections alternately, and having one broad shallow continuous smoke flue or passage extending similarly between the several sections, substantially as specified. 100

3. A hot-water heater composed of a series of sections laid one on top of another, and having one broad shallow continuous water space or passage the full width of the heater, extending in a series of folds or bends, one 105 above another, across the heater from side to side, the water-spaces of the contiguous sections communicating together by long narrow centrally-located ports at the ends of the sections alternately, and having one broad shallow continuous smoke flue or passage extending similarly between the several sections, 110 said water ways or passages forming a series of inclined planes one above another, substantially as specified. 115

4. A hot-water heater having one broad shallow continuous water space or passage extending in a series of nearly horizontal folds or bends, one above the other, across the heater from side to side and provided with a continuous smoke passage or flue extending in a similar series of nearly horizontal folds or 120 bends across the heater at right angles to the former, so that the currents of water and the currents of smoke or products of combustion will cross each other transversely as they pass through the heater in their respective 125 passages or flues, substantially as specified. 130

5. A hot-water heater composed of a series of sections laid one on top of another, each having a single broad shallow water-space the

full width of the section and provided with a smoke flue or passage between the sections, the water-spaces of said sections communicating together through long narrow ports located centrally at the sides of the heater-sections, so that the water in flowing from one port to another must cross the heater centrally, whereby the circulation of the water through the heater is facilitated, substantially as specified.

6. A hot-water heater composed of a series of sections laid one on top of another, each having a single broad shallow water-space the full width of the section and provided with a smoke flue or passage between the sections, the water-spaces of said sections communicating together through long narrow ports located centrally at the sides of the heater, so that the water in flowing from one port to another must cross the heater centrally, said water spaces or ways forming a series of inclined planes, one above another, so that the hot water can follow its natural tendency to rise as it flows through the heater, whereby the circulation of the water through the heater is facilitated, substantially as specified.

7. A hot-water heater composed of a series of sections laid one on top of another, said sections being each furnished with a single broad shallow water-space, the water-spaces of the contiguous sections being connected together by long narrow parts and provided with the single continuous smoke-flue between the sections, the surface or walls of said sections being corrugated to increase the heating-surface, substantially as specified.

8. In a hot-water heater, the combination of the ash-pit section A with fire-pot section B, fire-box section C, having a corrugated or convoluted inner wall, crown-sheet section D, intermediate sections G, and top section M, said sections communicating together by oblong centrally-located ports x, arranged alternately, and each of said sections D G M having a single broad shallow water-space the full width and length of the section and there being a single continuous smoke flue or passage formed by the connected spaces between the several sections, substantially as specified.

9. In a hot-water heater, the combination of the ash-pit section A with fire-pot section B, fire-box section C, having a corrugated or convoluted inner wall, crown-sheet section D, intermediate section G, and top section N, said sections communicating together by oblong centrally-located ports x, arranged alternately, said section B having a fire-brick lining B', and each of said sections D G M having a small broad shallow water-space the full width and length of the section, and there being a single continuous smoke flue or passage formed by the connected spaces between the several sections, substantially as specified.

10. The combination of a series of square or rectangular hot-water-heater sections B C D G M, said sections B C having a round cen-

tral fire-pot and box-opening and a water-space surrounding said fire pot and box, and said sections D G M each having a single shallow water-space extending the full width and length of the section, and the water-spaces of the several sections communicating together by long narrow centrally-located ports alternately arranged so as to produce a continuous S-shaped water-passage, and there being a similar continuous smoke flue or passage between the sections extending transversely to said water-passage, substantially as specified.

11. The combination of a series of square or rectangular hot-water-heater sections B C D G M, said sections B C having a round central fire-pot and opening, and a water-space surrounding said fire pot and box, and said sections D having a corrugated crown-sheet d, and said sections D G M each having a single shallow water-space extending the full width and length of the section, and the water-spaces of the several sections communicating together by long narrow centrally-located ports alternately arranged so as to produce a continuous S-shaped water-passage, and there being a similar continuous smoke flue or passage between the sections extending transversely to said water-passage, substantially as specified.

12. The combination of a series of square or rectangular hot-water-heater sections B C D G M, said sections B C having a round central fire-pot and box-opening and a water-space surrounding said fire pot and box, and said sections having a corrugated crown-sheet d, the water-spaces of said sections D G M forming a series of inclined ways or passages communicating together at opposite sides of the heaters by suitable ports, and said sections D G M each having a single shallow water-space extending the full width and length of the section, and the water-spaces of the several sections communicating together by long narrow centrally-located ports alternately arranged so as to produce a continuous S-shaped water-passage, and there being a similar continuous S-shaped smoke flue or passage between the sections extending transversely to said water-passage, substantially as specified.

13. The combination of a series of square or rectangular hot-water-heater sections B C D G M, said sections B C having a round central fire-pot and box-opening and a water-space surrounding said fire pot and box, and said sections having a corrugated crown-sheet d, the water-spaces of said sections D G M forming a series of inclined ways or passages communicating together at opposite sides of the heaters by suitable ports, substantially as specified.
